BACKSPLASH AND CONTROL PANEL FOR A RANGE

Carl W. Sundberg, Bloomfield Hills, Mich., assignor to Whirlpool-Seeger Corporation, St. Joseph, Mich., a corporation of Delaware

Application September 6, 1956, Serial No. 42,852

Term of patent 14 years

(Cl. D81—25)

Figure 1 is a perspective view of a backsplash and control panel for a range showing my design; and

Figure 2 is a side view thereof.

The body portion of the range is indicated fragmentarily and in broken lines for purposes of illustration. The dominant feature of the design resides in the portions shown in full lines.

I claim:

The ornamental design for a backsplash and control panel for a range, as shown and described.
